(57) **CLAIM**

The ornamental design for a combined heart inlay and portion of a ring, as shown and described.

DESCRIPTION

FIG. 1 is a perspective view of a combined heart inlay and portion of a ring shank therefore showing my new design; FIG. 2 is a front view thereof; FIG. 3 is a side view thereof; FIG. 4 is a front view of a second embodiment of FIG. 1 showing another location for the heart inlay; FIG. 5 is a front view of a third embodiment of FIG. 1 showing another location for the heart inlay; FIG. 6 is a front view of a fourth embodiment of FIG. 1 showing another location for the heart inlay; and, FIG. 7 is a side view of a fifth embodiment of FIG. 1 showing the heart inlay inside the shank of the finger ring. The broken lines of the remainder of the ring/shank are for purposes of illustration only and form no part of the claimed design.
